CABINET FOR COMBINED PHONOGRAPH AND FILM STRIP VIEWER

Richard E. Lee, Cazenovia, N.Y., and Kurt F. Mizen,
Chicago, Ill., assignors to General Electric Company,
a corporation of New York

Filed Aug. 25, 1964, Ser. No. 81,432

Term of patent 14 years

(Cl. D56—4)

FIG. 1.

FIG. 2.

FIG. 3.

FIG. 4.

FIG. 5.

FIG. 1 is a perspective view of a cabinet for combined phonograph and film strip viewer, showing our new design;

FIG. 2 is a front elevational view;

FIG. 3 is a top plan view;

FIG. 4 is a side elevational view, the side not shown being substantially the same in appearance; and

FIG. 5 is a bottom plan view.

The dominant features of the design reside in the portion shown in full lines.

We claim:

The ornamental design for a cabinet for combined phonograph and film strip viewer, substantially as shown and described.
